[57] CLAIM

The ornamental design for a video display game table, as shown and described.

DESCRIPTION

FIG. 1 is a perspective view of the video display game table. FIG. 2 is a front elevational view of the video display game table.

FIG. 3 is a rear elevational view of the video display game table.

FIG. 4 is a top plan view of the video display game table. FIG. 5 is a bottom plan view of the video display game table; and,

FIG. 6 is a right side plan view of the video display game table, the left side plan view being the mirror image thereof.

Broken lines illustrate features or environmental components that are not part of the design sought to be patented.
